UNITED STATES PATENT OFFICE.

GEORGE E. TYSON, OF READING, PENNSYLVANIA.

DESIGN FOR A DOOR-ESCUTCHEON.

SPECIFICATION forming part of Design No. 23,729, dated October 23, 1894.

Application filed September 27, 1894. Serial No. 524,314. Term of patent 7 years.

To all whom it may concern:

Be it known that I, GEORGE E. TYSON, a citizen of the United States, residing at Reading, county of Berks, State of Pennsylvania, 5 have invented a certain new and original Design for a Door-Escutcheon or Similar Article of Builders' Hardware, of which the following is a specification.

The main feature of my design is the representation of a series of balls arranged to form an ornamental border around the central portion of the plate as shown in the accompanying drawing.

Referring to the drawing which illustrates 15 my design, *a* represents the raised central portion of the plate, *b* a depressed ledge or shelf surrounding the central portion *a*, and *c* an ornamental extension of the plate beyond the ledge *a*. Upon the ledge *a* appears 20 a series of balls *d* projecting about half their

diameter above the surface of the ledge, and arranged close to each other so as to form a border line of balls apparently embedded in the ledge. These balls are represented as of gradually increasing size from the corners 25 toward the middle of the plate in either direction, and the width of the ledge is correspondingly increased at the middle and the raised central portion *d* of the plate correspondingly reduced as shown. 30

What I claim is—

The design for an escutcheon or similar article of builders' hardware substantially as shown.

In testimony whereof I affix my signature in 35 presence of two witnesses.

GEO. E. TYSON.
